UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

LID-SUPPORTING DEVICE.

1,337,791.

Specification of Letters Patent.

Patented Apr. 20, 1920.

Application filed September 10, 1919. Serial No. 322,783.

To all whom it may concern:

Be it known that I, STUART W. PARSONS, a citizen of the United States, residing at New Britain, in the county of Hartford, State of Connecticut, have invented certain new and useful Improvements in Lid-Supporting Devices, of which the following is a specification.

This invention relates to devices for supporting in raised position hinged parts, such as covers or lids of articles of furniture, boxes and the like and it has particular reference to supporting devices of the type wherein a prop-bar pivotally secured to the hinged cover or lid coöperates with a stationary bracket in such manner that when the cover is raised the prop-bar will be automatically brought to a seat in the bracket to maintain the cover in raised position and then when the cover is further raised the prop-bar is automatically withdrawn from said seat and moved into a position where the hinged cover may be lowered.

It is the object of the present invention to provide an improved bracket for guiding and supporting the prop-bar of a lid supporting device, which bracket is efficient in operation, simple in construction, strong and durable and which may be readily and quickly applied to articles of various kinds.

In the accompanying drawings:

Figure 1 is a side elevation of a preferred embodiment of my invention, the same being illustrated as applied to a talking machine cabinet although it is to be understood that it is not limited to this specific use, and

Fig. 2 is a bottom view of my improved bracket.

Referring to the drawings in detail, 10 designates a cabinet of a talking machine having, as is usual, a hinged cover 11 and a platform 12 provided with an elongated slot. Pivotally secured at its upper end to the hinged cover 11 is a prop-bar 13 having, 45 adjacent its lower end, a projection or stud 14.

My improved bracket comprises a top plate 15 overlying the slot in the platform 12 and having an elongated slot 15^a through 50 which the prop-bar 13 extends, and a guide plate 16 extending downwardly from one edge of the plate 15 and having a passageway through which the projection 14 of the prop-bar travels when the cover 11 is raised and lowered. The top plate 15 may be se-

cured to the platform in any suitable manner, as by means of indicated screws 17.

The guide plate 16 is preferably integral with the top plate 15, the entire bracket being by preference formed by stamping and pressing a single piece of sheet metal into proper form and shape. The guide plate 16 has a pair of ribs 18 and 19 leading upwardly from the lower edge of the guide plate and between these ribs is a rib or bridge 24, the upper edge of which is V-shaped to form the lower edge of a V-shaped slot 20, the upper edge of this slot being defined by the projection 25. The ribs 18 and 19 provide channels which together with the slot 20 form a passageway or guideway of substantially M-shape for the projection 14. Leading upwardly and rearwardly from the top of the channel in the rib 18 to the slot 20 is a slot 26 and these two slots form a slot similar in shape to a horizontally disposed capital Z. The depression in the upper edge of the bridge 24 forms a seat 21 into which the projection 14 of the prop bar is automatically brought when the hinged 80 cover 11 is raised into open position, as is clearly shown by dotted lines in Fig. 1. The forward wall of the bridge or rib 24 is inclined so as to form a cam surface 22 along which the projection or stud 14 of the prop bar rides when the cover is raised. The wall or cam surface 22 and the rear wall 27 of the rib 24 are such parts as respond to what is described in some of the claims as angularly disposed or opposite facing walls. 90

When the cover 11 is raised, the lower end of the prop-bar 13 swings forwardly or away from the hinged end of the cover until it is in vertical position; the stud 14 then moves upwardly into the channel of the rib 18 and rides up the inclined wall 22 into the forward end of the Z-shaped slot, further upward movement of the cover being limited when the projection 14 has moved into engagement with the edge 23 defining the top of the slot; the cover is allowed to fall slightly and thereupon, due to gravity, the lower end of the prop-bar swings rearwardly toward the hinged end of the cover and the projection 14 is automatically brought to rest in the seat 21, as shown by the dotted lines in Fig. 1. When it is desired to close down the cover, the cover is raised in a direction to further open the same, whereupon the projection 14 of the 110

prop-bar travels up the rear end of the V-shaped slot 20 until it is brought into registry with the channel in the rib 19 and then the cover may be lowered, the projection of course passing downwardly through the channel in the rib 19.

Brackets constructed in accordance with the present invention may be formed by merely stamping from a sheet of metal a blank conforming to the shape of the top plate 15 and the guide plate 16 and having the slot 20 in the guide plate; pressing out the ribs 18 and 19 in the guide plate, and then bending the top plate over at right angles to the guide plate. It will be seen that my improved bracket requires but very few and comparatively inexpensive and simple operations in its manufacture, all machining operations which usually materially add to the cost of production, are entirely eliminated, and therefore, my improved brackets may be manufactured in large quantities at a relatively low cost. The structure is extremely strong and durable particularly so since both of the ribs 18 and 19 support the bridge 24 therebetween having the seat 21 and on which portion the greatest strains are exerted when the cover is in open position. All strains on the guide plate, due to the engagement of the stud 14 on the edges of the Z-shaped slot in the plate, are exerted in the plane of the guide plate. It will further be noted that the bracket herein described may be readily and quickly applied to a talking machine cabinet or other receptacle, it being merely necessary, in installing the device, to insert the guide plate into the elongated slot in the platform 12 and then drive the screws 17 into place. The screws are in such position that they may be readily inserted, it being entirely unnecessary to gain access to the interior of the cabinet beneath the platform or insert any fastening means in any corner or place not readily accessible.

It is of course obvious that my invention is susceptible of various modifications and changes which are within the spirit of the invention without departing from the scope of the following claims, it being understood that the present disclosure of my invention is by way of illustration only and it is not to be taken as restrictive of my conception.

I claim as my invention:

55 1. A bracket for guiding and supporting a prop-bar of a lid supporting device and having a guide plate formed from a single piece of sheet metal and provided with a V-shaped slot and a rib, said slot and the channel in said rib opening into one another and forming a part of an M-shaped slot.

60 2. A bracket for guiding and supporting a prop-bar of a lid supporting device and having a guide plate formed from a single piece of sheet metal and provided with a

V-shaped slot and a rib forming a channel leading from the lower edge of the plate into one end of said slot, said slot having a seat for receiving a part on the prop-bar.

3. A bracket for guiding and supporting 70 a prop-bar of a lid supporting device and having a sheet metal plate provided with a V-shaped slot and a pair of ribs forming channels leading from the lower edge of said plate to opposite ends of said slot, said 75 slot having a seat for receiving a part on said prop-bar.

4. A bracket for guiding and supporting a prop-bar of a lid supporting device and comprising a sheet metal guide plate provided with a pair of vertically extending ribs forming channels leading from the lower edge of said bracket and terminating short of the top thereof and a horizontally disposed Z-shaped slot connecting said channels 85 at their upper ends, the rear wall of one of said channels being inclined.

5. A bracket for guiding and supporting a prop-bar of a lid supporting device formed from a single piece of sheet metal and comprising a top plate having an elongated slot, and a guide plate integral with and depending from one edge of said top plate and having a pair of channels leading upwardly from the lower edge thereof and terminating 95 short of the top plate and a Z-shaped slot connecting the upper ends of said channels.

6. A bracket for guiding and supporting a prop-bar of a lid supporting device, 100 including a guide plate formed from a single piece of sheet metal and having a wall upset out of the plane of said plate and extending from the lower edge thereof, and a slot in which said wall terminates and having a depression or seat in its lower edge.

7. A bracket for guiding and supporting a prop-bar of a lid supporting device, including a guide plate formed from a single piece of sheet metal and having a transverse 110 slot in its upper part, a bridge integral with the plate and having an upper V-shaped edge forming the lower edge of the slot and guiding walls extending from the lower edge of said bridge and terminating in the slot. 115

8. A bracket for guiding and supporting a prop-bar of a lid supporting device, including a guide plate formed from a single piece of sheet metal and having a transverse slot in its upper part, a bridge integral with 120 said plate and having an upper V-shaped edge forming the lower edge of said slot and upwardly diverging guiding walls extending from the lower edge of said bridge and terminating in the slot. 125

9. A bracket for guiding and supporting a prop-bar of a lid supporting device, including a guide plate formed from a single piece of sheet metal and having a pair of oppositely facing walls upset out of the plane 130

- of the plate and extending from the lower edge thereof and a slot in the plate between the upper ends of said walls and having a depression or seat in its lower edge.
- 5 10. A bracket for guiding and supporting a prop-bar of a lid supporting device, including a guide plate formed from a single piece of sheet metal and having a transverse slot in its upper part and an integral rib 10 having its upper edge V-shaped and forming the lower edge of the slot, the forward and rear walls of said rib being upset from the plane of said plate and extending from the lower edge thereof and terminating at 15 their upper ends in said slot.
- 11 A bracket for guiding and supporting a prop-bar of a lid supporting device formed from a single piece of sheet metal and comprising a top plate having an elongated slot 20 and a guide plate integral with and depend-
- ing from one edge of said top plate, said 25 guide plate having a portion bent out of the plane thereof to form a laterally extending wall leading from the lower edge of the plate and a V-shaped slot in said plate in which the upper end of said wall terminates. 30
12. A bracket for guiding and supporting a prop-bar of a lid supporting device formed from a single piece of sheet metal and comprising a top plate having an elongated slot and a guide plate integral with and depending from one edge of said top plate, said 35 guide plate having a transverse slot in its upper part and an integral rib below the slot and forming angularly disposed guiding walls leading upwardly from the lower edge 40 of the plate and terminating in the slot, the upper edge of said rib being V-shaped.

STUART W. PARSONS.
